ELECTRICAL SERVO SYSTEM

Alda V. Bedford, Princeton, N. J., assignor to
 Radio Corporation of America, a corporation
 of Delaware

Application December 30, 1944, Serial No. 570,624

13 Claims. (Cl. 318—28)

1

This invention relates to electrical servo systems, and more particularly to improvements in the art of stabilizing electrical servo systems of the type employing A.-C. control signals.

An electrical servo system, as the term is used herein, is defined as comprising an output shaft, an electric motor coupled to said shaft, means providing a "displacement signal" related in some characteristic, such as its amplitude, to the difference between the actual position of the output shaft and the position to which it is to be driven, and means for energizing the motor in response to the displacement signal, in such manner that the motor tends to drive the shaft to reduce the effect of the displacement signal, and hence the motor energization, to zero. It is well known to those skilled in the art that such systems tend to be inaccurate and sluggish if the displacement signal produces too little effect on the motor, and tend to overrun the correct position and "hunt". If the displacement signal is made sufficiently effective to overcome the effects of friction. It is common practice to combat these difficulties by adding to the displacement signal further signals which are in effect time derivatives of the displacement signal. If the displacement signal is a D.-C. voltage of variable magnitude, the proper auxiliary signals are also D.-C. voltages, having magnitudes which vary as the first and higher order time derivatives of the displacement signal. If the displacement signal is an A.-C. voltage of variable amplitude, the auxiliary signals must also be A.-C. voltages, of the same frequency as the displacement signal, varying in amplitude in accordance with the time derivatives of the amplitude of the displacement signal. It is important to note that the auxiliary voltage waves are not time derivatives of the displacement voltage wave.

The principal object of the present invention is to provide improved servo systems of the type wherein a variable amplitude A.-C. voltage is employed as the displacement signal, including means for producing auxiliary "derivatives" signals.

Another object is to provide improved methods of and means for deriving from a variable amplitude A.-C. voltage, further A.-C. voltages varying in their amplitudes in accordance with the time derivatives of the amplitude of said first voltage.

A further object is to provide an improved servo system adapted for automatically positioning directive radio antennas in response to radio signals picked up thereby.

2

These and other objects will become apparent to those skilled in the art upon consideration of the following description, with reference to the accompanying drawings, of which

5 Figure 1 is a schematic diagram of a radio locator system embodying the instant invention.

Figure 2 is a graph illustrating a variation of the position of the output shaft of the system of Figure 1 with respect to the correct position of said shaft.

10 Figure 3 is a graph illustrating variations with time of the amplitude of a radio signal received in the operation of the system of Figure 1.

Figure 4 is a graph illustrating the output of 15 the radio receiver of the system of Figure 1 under the conditions represented by Figures 1-3.

Figure 5 is a graph illustrating the voltage of Figure 4 after being delayed.

Figure 6 is a graph of the difference between 20 the voltages of Figures 4 and 5.

Figure 7 is a schematic diagram of a modification of one of the subcombinations of the system of Figure 1.

Figure 8 is a further modification of one of the 25 subcombinations of Fig. 1.

Figure 9 is a graph illustrating the voltage of Figure 4 after being delayed by a different amount than that corresponding to Figure 5, and

Figure 10 is a graph illustrating the sum of the 30 voltages of Figures 4 and 9.

Referring to Figure 1, only those elements of a radio locator system which are necessary to an explanation of the present invention are shown.

A radio transmitter 1 is connected through a two-way switch device 3 to a pair of radiators 5 and 7. The radiators 5 and 7 are directive, and are positioned upon a supporting member 9 in such manner that their directive patterns overlap with the maximum directivity of the radiator 5 lying in a line to the right of the equisignal axis, and that of the radiator 7 lying to the left. The supporting member 9 is rotatable by means of a shaft 11, which is coupled to a motor 13.

The switch 3 is coupled to a synchronous motor 45 15, arranged to be energized from an A.-C. source, not shown. The motor 15 may be arranged to drive the switch 3 at a constant speed of 3600 R. P. M., for example, connecting the transmitter 1 alternately to the radiators 5 and 7 at a rate of 60 cycles per second.

The motor 13 is illustrated as a commutator type A.-C. motor, although it is to be understood that any known type of reversible A.-C. motor may be used. The field winding of the motor 13 is connected through a phase shifter 17 to the

A.-C. supply. The armature of the motor 13 is connected to the output circuit of an amplifier 19.

A radio receiver 21, provided with an antenna 23, is tuned to the frequency of operation of the transmitter 1. The output circuit of the receiver 21 is coupled to the control grid of an electron discharge tube 25. The tube 25 is provided with two load resistors 27 and 29, connected in the anode and cathode circuits respectively. A grid leak 31 is also provided, with its lower end connected to a D.-C. source of biasing potential. The tube 25, with its associated resistors, constitutes a well known type of phase inverter. It will be apparent that any other known type of phase inverter may be substituted. The phase inverter is designated generally by the reference numeral 33 in Figure 1.

The anode of the tube 25 is coupled through a blocking capacitor 35 directly to the control grid of a tube 37, and through a resistor 39 to the control grid of a tube 41. The cathode of the tube 25 is coupled through a blocking capacitor 43, a delay network 45, and a resistor 47 to the control grid of the tube 41. The output end of the delay network 45 is also coupled through an amplifier 42 to the input circuit of a phase inverter 33', similar to the phase inverter 33.

The phase inverter 33' is coupled to the control grid of a tube 49 through resistors and a delay network, in exactly the same manner as the phase inverter 33 is coupled to the tube 41. The elements in the connections from the phase inverter 33' which are similar to those associated with the phase inverter 33 are denoted by corresponding reference numerals, primed. The tubes 37, 41 and 49 are provided with a common load resistor 51, which is coupled through a capacitor 53 to the input circuit of the amplifier 19.

The time delay networks 45 and 45' illustrated in Figure 1 are of the same general construction as low pass filters, and in fact are low pass filter circuits. They are designed to pass at least the fundamental frequency of the output signal of the receiver 21, and are terminated in such manner and provided with the proper number of sections to introduce a delay of substantially one cycle, i. e. if the signal is 60 cycles per second, the networks 45 and 45' each cause a delay of $\frac{1}{60}$ second. If desired, the networks can be designed to pass higher frequencies as well, subject only to the condition that the required $\frac{1}{60}$ second delay is provided. The networks are illustrated as comprising series inductors and shunt capacitors. It will be understood by those skilled in the art that series resistors may be used instead of series inductors, and other types of networks may be substituted for those shown in Figure 1.

The operation of the system of Figure 1 is as follows: The transmitter provides radio frequency output which is applied alternately to the radiators 5 and 7 through the switch 3. Although the transmitter 1 may be modulated, it is assumed for the sake of simplicity of description that it merely provides a continuous wave. The operation of the servo system is substantially the same whether or not the transmitter is modulated. Signal is radiated alternately by the radiators 5 and 7. If a reflecting target lies on a line midway between the directive axes of the radiators, the strength of the reflected signal is the same regardless of which radiator is energized. However, if the target is to the left of the equisignal line, the reflected signal is stronger while the radiator 7 is energized, and weaker when the radiator 5 is energized.

Figure 2 shows a typical variation of the deviation of the equisignal line from the line of sight to the target, such as would be caused by motion of the target toward the left. Referring to Figure 3, the amplitude of the reflected signal varies accordingly, the pulses L₂, L₃ etc. representing energy transmitted from the antenna 7 becoming larger, and the right pulses R₂, R₃ etc. becoming smaller. It should be understood that each of the pulses L and R of Figure 3 represents only the amplitude of the reflected wave. The pulse frequency is 60 cycles per second, i. e. 60 L pulses and 60 R pulses occur each second, but the frequency of the signal itself may be several hundred megacycles per second.

The reflected signals are picked up by the antenna 23, and amplified and detected by the receiver 21, providing an output voltage represented by the graph of Figure 4. This is a 60 cycle wave, increasing in amplitude with increase in the deviation or displacement of the line of sight from the equisignal axis. If the deviation were to the right, rather than the left, a wave similar to that of Figure 4 would be produced, but of opposite phase.

The receiver output is applied to the control grid of the tube 25, causing corresponding variations of the anode current thereof, and hence similar variations in the voltage drops across the resistors 27 and 29. Upon increase of the anode current of the tube 25, the voltage at the anode becomes less positive, referred to ground potential, and that at the cathode becomes more positive. The blocking capacitors 35 and 43 pass only the A.-C. components of these voltages; thus the voltage at the control grid of the tube 37 is similar in form to that applied to the input of the delay network 45, but 180° out of phase with it. The voltage input to the delay network is in phase with the receiver output. The output of the delay network 45 is similar to the input, but delayed one cycle. This voltage is represented by the graph of Figure 5.

The current through the resistor 39 is proportional to the A.-C. component of the anode voltage of the tube 25. The current through the resistor 47 is proportional to the output voltage of the network 45. Both of these currents flow through the resistor 40. The voltage drop across the resistor 40 is thus substantially proportional to the sum of the A.-C. anode voltage of the tube 25 and the output voltage of the delay network.

The voltage across the resistor 40 is represented by the graph of Figure 6. Since the voltage applied through the resistor 39 is identical with that represented by Figure 4, but reversed in phase, the wave of Figure 6 is actually the difference between those of Figure 4 and Figure 5. Therefore, the magnitude of each pulse of the wave of Figure 6 is proportional to the difference between successive pulses of the wave of Figure 4. The difference between successive pulses is proportional to the time rate of change of amplitude. Thus, the amplitude of the wave of Figure 6 is proportional to the rate of change of amplitude of the wave of Figure 4. When the wave of Figure 4 is increasing in amplitude, the derivative wave of Figure 6 is in phase with it. When the wave of Figure 4 is decreasing in amplitude, that of Figure 6 is out of phase with it.

The phase inverter 33' and the delay network 45' operate upon the differential signal appearing across the resistor 40 to provide at the control grid of the tube 49 a wave corresponding in amplitude to the rate of change of amplitude of the

differential signal. This voltage, appearing across the resistor 40', is proportional to the second derivative of the displacement. It will be apparent that further derivative signals may be produced by adding further networks similar to those illustrated.

The displacement voltage is amplified by the tube 37. The first and second derivative voltages are amplified by the tubes 41 and 49 respectively. The three voltages are combined in the common load resistor 51, which is made of a resistance considerably less than the impedances of the tubes 37, 41 and 49 so that the anode currents of the three tubes will be independent of one another. The relative magnitudes of the displacement component and the derivative components may be adjusted by varying the values of the resistors 39, 39', 40 and 40'.

The composite voltage across the resistor 51 is amplified by the amplifier 19 and applied to the motor 13. The motor 13 is energized thereby to rotate the shaft 11 and direct the antennas 5 and 7 toward the target. Initially, while the displacement is increasing, the derivative component aids the displacement signal, providing increased motor torque to overcome friction. The second derivative component also aids the displacement signal while the rate of change of displacement is increasing, to overcome inertia during acceleration of the motor 13, and bucks the displacement signal while the rate of change of displacement is decreasing. As the displacement signal decreases, the first derivative component bucks it, tending to deenergize the motor more rapidly so that the system will coast to a stop without overshooting. The second derivative signal also bucks the displacement signal while the rate of change of displacement is decreasing, tending to overcome the momentum of the moving parts. Thus, by properly proportioning the resistors to control the amplification of the derivative signals in accordance with the friction and mass of the motor 13 and its mechanical load, the system may be made to operate smoothly and accurately, without lag or hunting.

In the operation of the system of Figure 1, the voltage appearing at the amplifier 19 comprises three components: an undelayed displacement signal, a signal similar to the displacement signal but delayed by one cycle, and a signal similar to the displacement signal but delayed by two cycles. Considering the operation of the system from this viewpoint, rather than that of successive derivatives, it becomes apparent that some of the elements of the system of Figure 1 may be omitted without altering the mode of operation of the overall system. Referring to Figure 7, a single phase inverter tube 33'' is connected like the phase inverter 33 of Figure 1 to anode and cathode load resistors 27'' and 29'' respectively. The cathode load resistor 29'' is coupled through a blocking capacitor 33'' to a delay network 45'' which, like the delay networks of Figure 1, is designed to provide a delay of one cycle. The output of the network 45'' is connected to a second identical delay network 45''''. The anode of the tube 33'' is coupled through a blocking capacitor 35'' and a resistor 70 to the input circuit of the power amplifier 19. The output of the network 45'' is similarly coupled through a resistor 71 to the amplifier 19 and the output of the network 45''' is likewise coupled to the amplifier 19 through a resistor 72.

In the operation of the circuit of Figure 7, the displacement signal is transmitted without delay.

through the capacitor 35'' and the resistor 70 to the amplifier 19. It is transmitted in reverse phase through the network 45'', which introduces a delay of one cycle, and then through the resistor 71 to the amplifier 19. The third component, delayed by two cycles, travels through both of the networks 45'' and 45''' and the resistor 72 to the amplifier 19. The relative values of the resistors 70, 71 and 72 may be adjusted to provide the required proportionality between the three components. Thus the composite voltage applied to the amplifier 19 is identical with that applied to the amplifier 19 in the system of Figure 1, although the derivative voltages are not produced separately at any point in the circuit.

Refer to Figure 8. The circuit including the phase inverter 33 and delay network 45 of the system of Figure 1 may be replaced by a delay network 61, bridged by a resistor 63. The network 61 is similar in construction to the network 45, but designed to provide a delay of only one-half cycle. The delayed signal is applied to a resistor 65. The original signal is also applied to the resistor 65 through the resistors 63 and 67. The delayed signal is represented by the graph of Figure 9. This is added in the resistor 65 to the original signal, represented by the graph of Figure 4. Owing to the half cycle delay of the network 61, each pulse of the resultant voltage is proportional in magnitude to the difference between successive left and right pulses of the original signal. The first pulse has a magnitude $L_2 - R_1$, which, in the illustrated case, is merely L_2 . The second pulse has a magnitude $R_2 - L_2$, etc. Thus, the amplitude of the A.-C. component of the wave of Figure 10 is at all times proportional to the rate of change of amplitude of the wave of Figure 4. The low frequency component of the wave of Figure 10 is of no effect, since it is removed by the blocking capacitors in the power amplifier.

Although the invention has been described in connection with an electrical servo system associated with a radio locator, it will be understood that it is equally applicable to any A.-C. servo system, and may be employed as well for any other purpose which requires differentiation of the envelope of an A.-C. wave. The various graphs in the drawing illustrate rectangular waves. However, voltages of sinusoidal or other wave forms may be used, without altering the design or operation as described.

I claim as my invention:

1. In an electrical servo system including an output shaft, a motor coupled to said shaft, means for producing an A.-C. displacement signal of frequency f cycles per second and amplitude substantially proportional to the difference between the actual angular position of said shaft and the position to which said shaft is to be driven, and means for applying said displacement signal to said motor, anti-hunt means including a time delay network designed to provide a delay of length

65

$\frac{n}{2f}$

seconds, wherein n is an integer, means for applying said displacement signal to said delay network to produce a delayed displacement signal, and means for applying said delayed displacement signal to said motor, in addition to said original displacement signal.

2. In an electrical servo system including motor means adapted to be energized by an alter-

said motor and means for applying said signal to said amplifier, comprising a voltage combining circuit in the input circuit of said amplifier, means for applying said signal directly to said combining circuit, means including a delay network for deriving a difference voltage whose amplitude is proportional to the difference between the amplitude of each cycle of said displacement signal and the next succeeding cycle, means for applying said difference voltage to said combining circuit, and means for applying the output of said combining circuit to said amplifier.
